(57) **CLAIM**

The ornamental design for a gas griddle, as shown.

DESCRIPTION

FIG. 1 is a perspective view of the front and left sides of the gas griddle of the present invention with the cover seated on top;

FIG. 2 is a front view of the griddle with the cover seated on top;

FIG. 3 is a rear view of the griddle with the cover seated on top;

FIG. 4 is a right side view of the griddle with the cover seated on top;

FIG. 5 is a left side view of the griddle with the cover seated on top;

FIG. 6 is a top plan view of the griddle with the cover seated on top;

FIG. 7 is a bottom plan view of the griddle;

FIG. 8 is a further perspective view of the griddle with the cover removed;

FIG. 9 is a further front view of the griddle with the cover removed;

FIG. 10 is a further rear view with the cover removed;

FIG. 11 is a further right side view with the cover removed;

FIG. 12 is a further left side view with the cover removed;

and,

FIG. 13 is a further top plan view with the cover removed. The broken lines depict portions of the gas griddle that form no part of the claimed design.

1 Claim, 13 Drawing Sheets
